J. ECKHARD,
DRILL PRESS,
APPLICATION FILED APR. 8, 1921.

Patented Aug. 15, 1922.

Fig. 1.

UNITED STATES PATENT OFFICE.

JOHN ECKHARD, OF BUFFALO, NEW YORK.

DRILL PRESS.

1,426,052.

Specification of Letters Patent. Patented Aug. 15, 1922.

Application filed April 8, 1921. Serial No. 459,525.

To all whom it may concern:

Be it known that I, JOHN ECKHARD, a citizen of the United States, residing at Buffalo, in the county of Erie and State of New York, have invented certain new and useful Improvements in Drill Presses, of which the following is a specification.

This invention relates to improvements in drill presses, and more particularly to the frame work thereof.

In the larger sizes of drill presses, the tool-spindle is subjected to sufficient pressure when feeding the tool into a work-piece to cause flexing of the frame and thereby create a bending stress of the main column which causes a fluctuation in the degree of accuracy in the operation to an extent that is harmful for the finer class of work, such as die work, the making of machine tools, etc.

The primary object of my invention is to provide a drill press with a comparatively light frame having forwardly and rearwardly-projecting overhanging-portions; and to provide the frame with means whereby the upward thrust on the forwardly-projecting overhanging-portion caused by the feed pressure, is counteracted or resisted, the rearwardly-projecting overhanging-portion of the frame being braced or supported to absolutely prevent flexing of the main column.

A further object of my invention is to provide a machine of this type in which the means employed to counteract the upward thrust produced from feed pressure is adjustable so that when assembling the parts of the machine, the drill spindle may be accurately alined with the axis of the work table and so that the position of the parts will be maintained to assure accurate work at all times.

A further object is to provide a frame comprising two sections, one mounted on and secured to the other by a single point connection and having forwardly and rearwardly-projecting overhanging-portions from said point of connection and means for adjusting said overhanging-portions and maintaining their adjustments.

With the above and other objects in view, my invention consists in the novel features of construction and in the arrangement and combination of parts to be hereinafter described and more particularly pointed out in the subjoined claims.

In the drawings:—

Fig. 1 is a side elevation of a drill press embodying my invention.

Fig. 2 is a broken enlarged vertical section through the rear brace column and the adjacent parts to which opposite ends thereof are connected.

Fig. 3 is an enlarged transverse section taken on line 3—3, Fig. 2.

Similar numerals are used to designate similar parts throughout the drawings.

The numeral 4 designates the frame considered as a whole, said frame comprising a base 5, a standard or main column 6, and a head 7 bolted or otherwise secured to the standard or main column 6 by means of bolts 8, or otherwise. The head 7 has a forwardly-projecting overhanging-portion 9 and a rearwardly-projecting overhanging-portion 10, the forwardly overhanging-portion having two vertically alined bearings 11 in which the drill spindle 12 is journaled, and a horizontal bearing 13 in which one end of a counter-shaft 14 is journaled, the other end of said counter-shaft being journaled in a bearing 15 provided at the rear end of the rearwardly-projecting overhanging-portion 10 of the frame.

To the standard or main column is fitted a table-knee 16 on which is mounted a work table 17. Mechanism for feeding the drill spindle is carried by the head 7 and may be of any suitable arrangement, as this forms no part of my invention.

Secured to the base 5 are two bearing uprights, one designated by the numeral 18 and the other by the numeral 19. In these uprights is journaled the main shaft 20 of the machine which extends rearwardly through the rear bearing upright 19 and has a loose pulley 21 thereon and a driving pulley 22 secured thereto in any suitable manner. By means of a pedal and rod arrangement or other device, the belt (not shown) adapted to drive said main shaft may be shifted from the loose to the tight pulley, or reversely, and as the shifting means for this purpose forms no part of my invention and may be variously applied, I do not consider it necessary to illustrate the same in detail.

On the main shaft is a cone pulley 23, and alined therewith on the counter shaft 14 is a reversed cone pulley 24, a belt (not shown) being passed around both cone pulleys and being applied and operated in

the usual manner to drive the countershaft from the main shaft.

At the rear end of the rearwardly-projecting overhanging-portion 10 is a depending portion 25 having its lower end turned down to cylindrical form, as at 26, to form a stud, the depending portion being provided with a beveled shoulder 27, for a purpose to appear hereinafter.

10 The rear bearing upright 19 is provided with a socket member in the form of an upward extension 28 having a socket 29 formed therein, said socket being counterbored, as at 30.

15 The head 7 of the frame is secured between its ends to the main column by what I term a "single-point" connection; the contacting faces of said connection being machined, but since the slightest inaccuracy 20 in this connection will throw the drill spindle out of proper position, I employ what I term a brace column 31, which is tubular and comparatively slender. The upper end of this brace receives the stud 26 25 on the depending portion of the head 7, and the upper edge thereof is flared, as at 32, to conform to the beveled shoulder 27 formed on said depending portion. Said stud is provided centrally with a down- 30 wardly opening slot 33, and a retainer pin 34 is passed through the walls of said brace column and through the slot 33 to prevent rotation of said brace column. By arranging the pin 34 within the slot 33, the upper 35 end of the brace column may be forced firmly against the beveled shoulder 27.

Driven into the lower end of said tubular brace column is a reinforcing and guide plug 35, said plug being fastened therein by 40 means of pins 36, preferably arranged at right angles to each other, the pins being passed through said tubular column and through said plugs, as clearly shown in Fig. 3. The reinforcing and guide plug 35 ex- 45 tends from the lower end of said tubular column and the exterior of said tubular column is screw-threaded, as at 37. The depending portion of said reinforcing and guide plug is entered in the lower or smaller 50 portion of the socket 29 and has a guiding fit therein, while the lower end of the tubular column is entered in the counterbored portion 30 of said socket, said counterbored portion being of slightly greater diameter 55 than the exterior diameter of said column.

Threaded onto the lower portion of said tubular column is an adjusting nut 38, which bears against the upper end of the socket member 28 on the bearing upright 19. By 60 means of said nut, the base column can be forced upwardly against the beveled shoulder on the depending portion 25 of the head 7, with proper pressure to maintain the drill spindle 12 in proper alinement 65 with the axis of the work table 17, and said

column will counteract or resist any upward thrust created by the upward pressure of the drill spindle caused when operating upon a work piece. With the adjusting nut 38 properly adjusted, it is locked in place 70 by means of a lock nut 39, also threaded on the lower threaded end of said brace column and bearing against said adjusting nut. Any play or looseness at the ends of the tubular brace column that may be caused 75 by continual and long use of the machine can thereby be easily taken up by means of the adjusting nut 38.

By means of the arrangement described, all bending stress is removed from the main 80 column, due to the counter-acting resistance offered by the brace column, the brace column being situated directly opposite the drill spindle and having its ends fastened to the rear extremity of the frame and extended base, as clearly shown in Fig. 1.

The application of this improved brace column or "back column", as it may be termed, equips the machine or frame with a counter-acting force which cannot be varied 90 by the feed pressure against a work piece, and therefore the degree of accuracy at the spindle is incapable of variance.

Having thus described my invention, what I claim is:—

1. A drill press having a frame provided with a rearwardly-projecting portion at its upper end and a rearwardly-extending portion at its lower end, a pair of bearing uprights secured to said rearwardly-extending 100 portion, one of said bearings having an upwardly opening socket formed therein, a drive shaft journaled in said bearing uprights, and a tubular brace column having connection at its upper end with said rearwardly-projecting portion and its lower end externally threaded and entered in said upwardly opening socket, and a nut threaded onto said externally threaded lower end and bearing against the upper end of the bearing upright having said socket therein. 105

2. A drill press comprising a frame having a base provided with a rearwardly-extending portion, a main column rising from said base and a head secured to said main column and provided with a rearwardly-projecting portion alined with the rearwardly-extending portion of said base, a comparatively slender column secured at its upper end to the extremity of the rearwardly-projecting portion of said head, and a socket member on the rearwardly-extending portion of said base, the lower end of said slender column being adjustable in said socket member. 115

3. A drill press comprising a frame having a rearwardly-projecting portion at its top and a rearwardly-extending portion at its bottom, a column having a part of said rearwardly-projecting portion entered in its 130

upper end, and a socket member rising from said rearwardly-extending portion at the bottom of said frame and having the lower end of said column adjustable therein.

5. A drill press comprising a frame having a base and a head provided with a rearwardly-projecting overhanging-portion, said overhanging-portion having a downwardly-facing beveled shoulder and a stud depend-
10 ing from said shoulder and provided with a pin slot opening at its lower end, a tubular column connecting said head with said base and having said stud entered into the upper end thereof, the upper edge of said tubular column being flared to fit the beveled shoulder of said head, and a pin extending through the tubular column and the slot of said stud.
5. A drill press comprising a frame hav-
20 ing a base, a main column provided with a head at its upper end having a rearwardly-projecting overhanging-portion, a socket member secured to said base in rear of said main column, said socket member having its
25 socket counterbored, a second and smaller column parallel with said main column having its upper end connected to the rearwardly-projecting overhanging-portion of said head and its lower end externally

threaded and provided with a plug project- 30 ing therefrom, said plug entering and being guided in the smaller portion of said socket and the lower extremity of the threaded end of said column entering the counter-bore of said socket, and a nut threaded onto the ex- 35 ternally threaded lower end of said tubular column and bearing against said socket member.

6. A drill press comprising a frame hav- 40 ing a base, a main column provided with a head having a rearwardly-projecting overhanging-portion, a socket member on said base, a tubular member connected to the rearwardly-projecting overhanging-portion of said head and having its lower end ex- 45 ternally threaded, a plug secured within the lower end of said tubular member, said socket member having a bore into which the lower end of said plug slidably fits and hav- 50 ing a counter-bore loosely receiving the lower end of said tubular member, an adjusting nut threaded onto said tubular member and bearing against said socket member, and a jam nut also threaded on said tubular member and bearing against said ad- 55 justing nut.

In testimony whereof I affix my signature.
JOHN ECKHARD.
